STRAND REELING APPARATUS

Tillman T. Bunch, near Ashland, Md., assignor to Western Electric Company, Incorporated, New York, N. Y., a corporation of New York

Application April 28, 1955. Serial No. 504,498

6 Claims. (Cl. 242—25)

This invention relates to strand reeling apparatus and more particularly to apparatus for distributing relatively thin and fragile strands uniformly upon takeup reels.

In the reeling of a strand upon a takeup reel it is desirable that the strand be distributed uniformly along the entire length of the reel from one flange thereof to the other. In reeling operations, wherein a continuously advancing relatively thin and fragile strand is reeled upon successive takeup reels without interrupting the advance of the strand, considerable difficulty has been encountered heretofore in providing suitable strand distributing means capable of achieving the necessary rapid and smooth changes in the distribution rate thereof, when the strand is transferred instantaneously from a full reel to an empty reel.

An object of this invention is to provide new and improved strand reeling apparatus.

Another object of this invention is to provide new and improved apparatus for distributing relatively thin and fragile strands uniformly upon takeup reels.

Strand reeling apparatus illustrating certain features of the invention may include a pair of reels, means for rotating each of the reels independently of the other and means for alternately transferring a strand being reeled from one of said reels to the other. A reciprocable means distributes the strand between opposite ends of the reel upon which the strand is being reeled, and means are provided for actuating the distributing means at any given time at a rate proportional to the algebraic sum of the instantaneous rotational speeds of the takeup reels at that time.

A complete understanding of the invention may be had from the following detailed description of apparatus forming a specific embodiment thereof, when read in conjunction with the appended drawings, in which:

Fig. 1 is a fragmentary, top plan view of a strand reeling machine with parts thereof broken away for clarity;

Fig. 2 is an enlarged side elevation of a portion of the apparatus shown in Fig. 1 with parts thereof broken away for clarity;

Fig. 3 is an enlarged, fragmentary portion of the apparatus shown in Fig. 2 with parts thereof broken away for clarity;

Fig. 4 is a fragmentary, horizontal section taken along line 4-4 of Fig. 3;

Fig. 5 is an enlarged, fragmentary portion of the apparatus shown in Fig. 1;

Fig. 6 is an enlarged, fragmentary, vertical section taken along line 6-6 of Fig. 1;

Fig. 7 is an enlarged, fragmentary, vertical section taken along line 7-7 of Fig. 2, and Fig. 8 is a schematic representation of a hydraulic circuit.

Referring now to the drawings, there is shown in Figs.

Referring now to the drawings, there is shown in Figs. 1 and 2 a strand takeup machine for reeling up a relatively thin and fragile strand 10, which is advanced continuously at a constant linear speed from an insulating machine (not shown), without interrupting or slackening the travel of the strand. The strand takeup machine includes a base 11 designed to be mounted fixedly upon a floor or other foundation. Formed integrally with the base 11 is

2

a hollow, upright column 12 on which is mounted, with freedom to rotate thereon, a bilaterally symmetrical, reel-carrying frame, indicated generally by the numeral 15, comprising a base portion 16, a top casing 17, and an intermediate central pillar 18, by which latter the lower base portion 16 and top casing 17 are spaced apart and held together.

Spaced 180° apart at each side of the frame 15 are stationary, upright members 20 and 21 which support the opposite ends of a horizontal crossmember 22. Supported fixedly by the crossmember 22 is a depending, generally cylindrical, journal housing 24. Journalled within the lower end of the journal housing 24 on a suitable bearing 25 is a central, cylindrical collar 27 projecting upwardly from the top casing 17 of the frame 15.

The entire frame 15 is rotatable on the column 12 and is provided on the opposite ends of the top casing 17 with two identical, cupped, latch receptacles 28-28. The latch receptacles 28-28 cooperate with complementary, 20 slideable latch members 29-29 mounted on brackets 30-30 positioned 180° apart. One of the brackets 30-30 is secured fixedly to the upright member 21 and the other bracket is secured fixedly to a vertical support 31. The 25 latch members 29-29 are designed to be releasably engaged in latch receptacles 28-28 to support the frame 15 and hold it in either of two operating positions located 180° apart.

The frame 15 and its associated parts are designed to support and drive a pair of takeup reels 35 and 36. A pair of freely rotatable, bearing centers 38 and 39 are mounted in the base portion 16 of the frame 15 to enter central, axial sockets (not shown) formed in lower reel heads 40 and 41 of the takeup reels 35 and 36 to support the reels. The bearing centers 38 and 39 are retractable downwardly by a suitable mechanism (not shown) actuated by levers 42 and 43 to be disengaged individually from the takeup reels 35 and 36. The base portion 16 of the frame 15 is further provided with fixed, circular, bottom reel guards 44 and 45 coaxial with and slightly larger in diameter than the adjacent lower reel heads 40 and 41.

At their upper ends the takeup, reels 35 and 36 are centrally engaged by spring-pressed, drive centers 46 and 47 (Figs. 2 and 3) which enter central axial sockets (not shown) formed in upper reel heads 48 and 49. The drive centers are resiliently seated in the lower ends of reel drive shafts 51 and 52, and are designed to rotate with their respective drive shafts. The drive shafts 51 and 52 are suitably supported for rotation in anti-friction bearings 54 and 55 and are provided with pulleys 57 and 58, respectively, keyed thereto in coaxial relation.

The pulley 57 is connected by a belt 59 to a drive pulley 60, which is keyed upon a vertical, central drive shaft 62 (Fig. 2) rotatably journaled at its opposite ends in suitable anti-friction bearings carried by the journal housing 24 and the column 12. Near its upper end, the central drive shaft 62 has keyed thereto a pulley 64 which is driven by a corresponding belt 65 (Figs. 1 and 2) from a pulley 67. The pulley 67 is driven by a constant horsepower, electric motor drive unit 70 having a controlled maximum speed, to which drive unit it is operatively connected through a conventional gear reduction unit 71.

The pulley 58 is driven by a corresponding belt 72 from a pulley 74 keyed to a vertical, coaxial drive shaft 75 freely rotatable upon the central drive shaft 62 between pulleys 60 and 64. The drive shaft 75 is driven by a pulley 77 integral therewith, and the pulley 77, in turn, is driven by a corresponding belt 78 from a pulley 79. The pulley 79 is driven by a constant horsepower electric motor drive unit 80 (Fig. 1), similar to the drive unit 70, having a controlled maximum speed. The pulley 79 is operatively connected to the drive unit 80 through a conventional gear reduction unit 81.

Rotary, constant displacement, hydraulic pumps 84 and 85 (Fig. 1) are operatively connected to the drive units 70 and 80, respectively, through their associated gear reduction units 71 and 81, respectively. As shown in Fig. 8, the pumps 84 and 85 are connected in parallel to hydraulic conduits 87 and 88, which, in turn, are connected through a spool type, four way, reversing valve 90 to a rotary, constant displacement, hydraulic distributor motor 92. Whenever either one or both of the hydraulic pumps 84 and 85 are operated, hydraulic fluid from a reservoir 93, which communicates with the conduit 87, is circulated under pressure through the conduits 87 and 88 in the direction indicated by the arrows in Fig. 8. Check valves 94—94 prevent the reverse flow of hydraulic fluid through the hydraulic pumps 84 and 85. By virtue of this arrangement, the hydraulic pumps 84 and 85 drive the distributor motor 92 at a speed proportional to the algebraic sum of the speeds of the drive units 70 and 80 and in a direction dependent upon the position of a slideable control spool 95 forming part of the reversing valve 90.

The distributor motor 92 (Fig. 2) is mounted to a base plate 97, and is provided with an output shaft 99 connected operatively to drive a distributor carriage 100 slidably mounted on spaced, vertical, parallel guide rods 102—102. The guide rods 102—102 (Fig. 7), are attached fixedly at their upper ends to the bracket 30 secured to the support 31 and at their lower ends to the baseplate 97.

Formed integrally with the distributor carriage 100 is a laterally projecting plate 104, which is attached fixedly to a vertical leg of an endless, flexible, non-slip, transmission belt 105 provided on its drive surface with molded teeth 106—106 of Neoprene compound. A suitable belt of this type is the Gilmer "Timing" belt manufactured by New York Belting and Packing Company, Passaic, New Jersey. The belt 105 is arranged in a vertically extending loop around a toothed drive pulley 107 keyed on the shaft 99 of the distributor motor 92 and a toothed idler pulley 108. The idler pulley 108 is keyed on one end of a horizontally extending operating shaft 109 of a valve reversing mechanism which is indicated generally by the numeral 110.

The shaft 109 is mounted rotatably on suitable anti-friction bearings 112 and 113 mounted, respectively, on the support 31 and a bracket 114 projecting vertically from the outer end of a laterally projecting bracket plate 115 which is attached to the outer side of the support 31. The valve reversing mechanism 110 (Fig. 6) also includes a generally triangular shaped mounting plate 117 fixedly secured near one of its apexes to the shaft 109 for oscillatory movement therewith in a plane perpendicular to the axis of that shaft. Mounted pivotally on pivot pins 118 and 119 near the other two apexes of the mounting plate 117 are a pair of depending hammer arms 121 and 122, respectively.

Attached to the ends of the hammer arms 121 and 122 adjacent to the pivot pins 118 and 119 (Fig. 6) are projecting, eccentric lugs 123 and 124, respectively, which are connected resiliently to an anchor post 126 by associated tension springs 127 and 128. The anchor post 126 is fixed to the mounting plate 117 in alignment with and midway between the pivot pins 118 and 119. The tension springs 127 and 128 normally urge the hammer arms 121 and 122 into the positions in which they are shown in Fig. 6, so that the line of action of each of the tension springs intersects the center of rotation of its associated hammer arm.

Mounted fixedly on the outer side of each of the hammer arms 121 and 122, near the free end thereof, is a shock-absorbing cushion member 130 made of Neoprene compound, or the like. The cushion members 130—130 on the hammer arms 121 and 122 are designated to strike alternately the opposite ends of the slideable control spool 95 of the reversing valve 90, which is mounted fixedly

on the bracket plate 115 beneath the mounting plate 117 in the path of the hammer arms. Spaced from each end of the reversing valve 90 and mounted fixedly to the bracket plate 115 are upwardly projecting detents 132 and 133. These detents 132 and 133 are designed to engage and hold momentarily the free ends of the hammer arms 121 and 122, respectively, as they are carried clockwise and counterclockwise by the oscillating mounting plate 117 so that the hammer arms 121 and 122 will strike the ends of the slideable control spool 95 with sharp blows.

When the hammer arms 121 and 122 alternately strike the slideable spool 95 of the reversing valve 90, they shift the spool axially in one direction or the other to cause the reversal of the distributor motor 92. The hammer arm 121 is designed to strike the right hand end of the spool 95, as viewed in Fig. 6, when the distributor carriage 100 reaches the upper limit of its traverse, and the hammer arm 122 is designed similarly to strike the left hand end of the spool when the distributor carriage reaches the lower limit of its traverse.

Projecting outwardly and laterally from the distributor carriage 100, as viewed in Figs. 2 and 7, are a pair of elongated, spaced, parallel fingers 135 and 136, between which the strand 10 advances on its way to the takeup reels 35 or 36. As the strand 10 is reeled upon the takeup reels 35 or 36, the distributor carriage 100 is reciprocated up and down and the fingers 135 and 136 guide the strand to insure a uniform distribution of the strand convolutions on the reels.

Each of the drive shafts 51 and 52 is provided at its lower end with an integral collar 140 (Fig. 3) to which is rigidly attached a plurality of radially, horizontally extending snagger arms 144—144. These snagger arms 144—144 are made of stiffly elastic material and are curved slightly downwardly. Each of the snagger arms 144—144 is formed at its outer extremity with a head 145 (Fig. 4), flattened horizontally and formed with a wedge-shaped notch 146.

The snagger arms 144—144 are partly enclosed by reel guards 150 and 151 attached fixedly to the under surface of the top casing 17 at each end thereof. These reel guards 150 and 151 are rigid, slightly cupped discs, positioned over the takeup reels 35 and 36, respectively, coaxially therewith, and are slightly larger in diameter than the reels. Each reel guard 150 and 151 is formed with a slot 152 (Figs. 1 and 5) extending inwardly from the periphery of the guard at an acute angle to the radial direction of the guard at the mouth of the slot. Upwardly projecting strand guide pins 154 and 155 are mounted rigidly on the top of each of the reel guards 150 and 151 (Fig. 5), one on each side of each of the slots 152—152.

Snagger arms and reel guards similar in construction to those hereinabove described, are disclosed and claimed in Brillhart et al. Patent 1,988,437.

Positioned on the upright member 21 is an electrical control panel 160 on which three pushbutton switches 161, 162 and 163 are mounted within easy reach of an operator. The pushbutton switch 161 is connected to a suitable circuit (not shown) including conventional relays and the like for controlling the energization of the drive units 70 and 80. The switch 161 is designed to deenergize and stop both of the drive units 70 and 80 when depressed. The pushbutton switch 162 is also a part of the above-mentioned circuit and is designed when depressed momentarily to energize the drive unit 70 and stop the drive unit 80 after a predetermined time delay. If the drive unit 80 is operating and the pushbutton switch 162 is depressed momentarily, the drive unit 70 is started immediately to bring the peripheral drum speed of the takeup reel 35 to within $\frac{1}{10}$ of the linear speed of the continuously advancing strand 10. After a predetermined time interval (e. g. 15 seconds) the drive

unit 80 is automatically deenergized and the takeup reel 36 stops, and thereafter the drive unit 70 drives the reel 35 to reel up the strand 10 under substantially constant tension. Contrawise, the pushbutton switch 163 is designed, when depressed momentarily, to start the drive unit 80 immediately and stop the drive unit 70 after the predetermined time interval. It will be understood that this predetermined time interval may be preselected within limits.

Operation

To facilitate the description of the operation of the takeup machine, let it be assumed that the motor drive unit 80 is presently energized and is driving the takeup reel 36 to reel the strand 10 thereupon, as the latter advances continuously from left to right, as viewed in Fig. 1, at a constant predetermined speed. The motor drive unit 80 maintains a constant horsepower output so that the rotational speed of the takeup reel 36 decreases in direct proportion to the increase in the winding radius of that reel, thereby maintaining a constant predetermined tension on the advancing strand 10. Throughout the reeling of the strand 10 upon the takeup reel 36, the hydraulic pump 85 is driven by the motor drive unit 80 at a speed directly proportional to the rotational speed of the reel 36, and operates the hydraulic distributor motor 92.

Since it will be assumed that the motor drive unit 70 is inoperative and the takeup reel 35 is stationary, the rate of operation of the distributor motor 92 is determined solely by the speed of the hydraulic pump 85. Hence, the speed of the shaft 99 of the distributor motor 92 is directly proportional to the speed of the hydraulic pump 85, and, therefore, is directly proportional to the rotational speed of the takeup reel 36. The distributor motor 92 rotates the drive pulley 107 to drive the belt 105 around the idler pulley 108 at a speed proportional to the rotational speed of the takeup reel 36. As the idler pulley 108 is so driven, it rotates the mounting plate 117 either clockwise or counterclockwise, as viewed in Fig. 6, depending upon the direction of movement of the belt 105.

Let it be assumed that the distributor carriage 100 is instantaneously at the upper limit of its traverse, as shown in Fig. 2. The mounting plate 117 of the valve reversing mechanism 110 then will be so positioned, as shown in Fig. 6, that the cushion member 130 of the hammer arm 121 will have just struck the right hand end of the control spool 95 to operate the valve 90 so as to reverse the distributor motor 92.

Immediately upon reversal of the distributor motor 92, the belt 105 is driven in a clockwise direction, as viewed in Fig. 7, to move the distributor carriage 100 downwardly. Simultaneously the idler pulley 108 is driven by the belt 105 to rotate the operating shaft 109 of the valve reversing mechanism 110 in a counterclockwise direction as viewed in Fig. 6. The downward movement of the distributor carriage 100 and the counterclockwise rotation of the mounting plate 117 (Fig. 6) continues until the control spool 95 of the reversing valve 90 is operated again by the hammer arm 122.

As the distributor carriage 100 nears the limit of its downward traverse the free end of the hammer arm 122 is engaged by the detent 133 which momentarily holds the hammer arm. Finally, when the distributor carriage 100 reaches the limit of its downward traverse, the hammer 122 rides over the detent 133 and the energy which has been stored in its associated tension spring 123 is released suddenly to drive the cushion member 130 against the left hand end of the control spool 95 with sufficient force to shift it fully to the right, so as to operate the reversing valve 90 to reverse the distributor motor 92. The distributor carriage 100 immediately reverses its direction and moves upward again until the reversing

valve 90 is again operated at the limit of its upward traverse.

Thus, the strand 10 is distributed to and fro across the takeup reel 36 from the inside of the lower reel head 41 to inside of the upper reel head 49 at a rate directly proportional to the rotational speed of that reel so as to achieve a uniform distribution of the convolutions of the strand upon the reel. Manifestly, the lead of the latter convolutions remains constant at a predetermined value throughout the reeling operation as long as the rate of distribution remains directly proportional to the rotational speed of the takeup reel 36.

When the takeup reel 36 is almost full and an operator desires to change the reeling of the strand 10 to the now empty and stationary takeup reel 35, the latch members 29-29 are disengaged from the latch receptacles 28-28 and the entire frame 15 is rotated 180° counterclockwise, as viewed in Fig. 1, until the latch members are again engaged. Thus, the positions of the reels 35 and 36 are interchanged without interrupting the reeling of the strand 10 upon the takeup reel 36. Subsequently, the operator depresses the pushbutton switch 162 whereupon the drive unit 70 is energized and immediately brings the peripheral drum speed of the empty reel 35 up to substantially the same speed as that of the advancing strand 10. After depressing the pushbutton switch 162, the operator has a predetermined time interval (e. g. 15 seconds) to perform a cutover operation in which the strand 10 is severed and the new leading end thereof is attached to the now empty takeup reel 35.

To achieve the cutover, the operator lifts the strand 10 manually from its path of travel, and without interrupting or affecting appreciably its motion, slips it through the slot 152 on the takeup reel 35 between the upwardly projecting guide pins 154 and 155. The next snagger arm 144 which passes the slot 142 catches the strand 10 in the notch 146 formed in its head 145, and severs the strand at once against a sharp lower edge 170 formed on the trailing edge of the slot. Simultaneously the snagger arm 144 jams the new leading end of the strand 10 beneath the underface of the snagger arm head 145 and the upper face of the upper reel head 48 of the takeup reel. Thus, the strand 10 is practically instantaneously caught, cut and attached to the then empty reel 35 to be subsequently reeled thereupon without interrupting or affecting appreciably its motion and tension. Immediately thereafter, at the end of the short predetermined time interval, the drive unit 80 is deenergized and the takeup reel 36 containing a finished strand package stops rotating.

During the short time interval in which the drive unit 70 is energized and brings the peripheral drum speed of the takeup reel 35 up to match the linear speed of the strand, the hydraulic pump 84 is likewise started and brought up to speed. Manifestly, the hydraulic pump 84 will have an additive effect upon the speed of the distributor motor 92 and cause it to speed up. Accordingly, the rate of distribution of the strand 10 upon the full takeup reel 36 will increase and, for the short time that the takeup reel 36 continues to operate, the lead of the convolutions in the last layer thereon will be greater than the normal, predetermined lead. However, the latter effect is beneficial because the last applied convolutions will overlay the adjacent layer of convolutions at a greater angle and tend to restrain uncoiling when the strand 10 is severed and the takeup reel 36 is stopped.

The additive effect of the simultaneously operating hydraulic pumps 84 and 85 also aids in bringing the speed of the distributor carriage 100 rapidly up to that required to form strand convolutions on the empty reel 35 having a lead at least equal to the predetermined lead. At the time the cutover is performed to transfer the strand 10 from the full reel 36 to the empty reel 35, the speed of the distributor carriage 100 will be

greater than that required to achieve the reeling of the strand 10 upon the takeup reel 35 with convolutions having the predetermined lead.

This, likewise, is desirable because the lead will be greater for the first few convolutions formed on the reel 35 than that of subsequently applied convolutions, and the few first applied convolutions will be bound upon the reel by the latter. Because the drive unit 80 is stopped almost immediately after the strand 10 is transferred to the takeup reel 35, the number of convolutions formed having a lead greater than the predetermined lead is relatively negligible and confined substantially to the initial layer of convolutions. Manifestly, as soon as the drive unit 80 stops, the distribution rate is determined only by the pump 86 and thereafter the lead of convolutions formed is equal to the normal predetermined lead.

It will be understood that it is the novel arrangement whereby the hydraulic pumps are connected in parallel, which facilitates a rapid transition from the slow distribution rate required for uniform distribution of the strand 10 upon the full reel 36 to the faster distribution rate required for the uniform distribution of the strand upon the empty takeup reel 35. At the time the reeling of the strand upon the takeup reel 35 commences, this faster distribution rate causes the convolutions at the start to have a lead at least equal to the predetermined lead. If the latter condition is not obtained, the strand convolutions, instead of laying side by side in a particular layer, would tend to pile up, one on top of the other, and the result would be a soft or rough strand package instead of a firm package which is desired. It may be readily seen that in the above-described apparatus the control of the distribution of the strand during the cutover operation is inherent, as contrasted to conventional apparatus which require the shifting of clutches, gears or the like during the transfer from one takeup reel to another.

Manifestly, the above-described embodiment of the invention is given merely by way of example, and numerous arrangements and modifications thereof may be made within the spirit and scope of the invention. It will be understood that although the apparatus hereinabove described is designed for reeling strand-like materials, such as wire, this invention is not limited to such practice, since other materials, such as paper in take form, textile strands, and the like, may be taken up on the reels.

What is claimed is:

1. Strand reeling apparatus which comprises a pair of reels, means for rotating each of said reels independently of the other, means for alternately transferring a strand being reeled from one of said reels to the other, reciprocable means for distributing the strand between opposite ends of the reel upon which the strand is being reeled, and means connected operatively to the independent rotating means of both reels simultaneously and powered thereby for actuating the distributing means at any given time at a rate proportional to the algebraic sum of the instantaneous rotational speeds of the takeup reels at that time.

2. Strand reeling apparatus which comprises a pair of takeup reels, means for rotating each of said reels independently of the other, means for alternately transferring a strand being reeled from one of said reels to the other, a strand distributor mounted reciprocably for distributing the strand between opposite ends of the reel upon which the strand is being reeled, and hydraulic means for actuating the strand distributor reciprocably at any given time at a rate proportional to the algebraic sum of the instantaneous rotational speeds of the takeup reels at that time.

3. Strand reeling apparatus which comprises a pair of takeup reels, means for rotating each of said reels independently of the other, means for alternately transferring a strand being reeled from one of said reels

to the other, reciprocable means for distributing the strand between opposite ends of the reel upon which the strand is being reeled, a reversible hydraulic motor for actuating the distributing means reciprocably, and a pair of hydraulic pumps operatively connected to the respective takeup reels for operating the hydraulic motor at any given time at a speed proportional to the algebraic sum of the instantaneous rotational speeds of the takeup reels at that time.

4. Strand reeling apparatus which comprises a pair of takeup reels, separate drive means for rotating each of said reels independently of the other, means for alternately transferring a strand being reeled from one of said reels to the other, a strand distributor mounted reciprocably for distributing the strand to and fro between opposite ends of the reel upon which the strand is being reeled, a reversible hydraulic motor for actuating the strand distributor reciprocably, a pair of hydraulic pumps for operating the motor, said pumps being driven respectively by the separate drive means for the respective takeup reels at speeds directly proportional to the rotational speeds of their respective takeup reels, and means connecting the hydraulic pumps in parallel hydraulically whereby the hydraulic motor at any time is operated at a speed proportional to the algebraic sum of the instantaneous rotational speeds of the takeup reels at that time.

5. Strand reeling apparatus which comprises a pair of takeup reels, separate drive means for rotating each of said takeup reels independently of the other, means for alternately transferring a strand being reeled from one of said takeup reels to the other, a distributor carriage slidably mounted for movement parallel to the longitudinal axes of said takeup reels, an endless belt to which the distributor carriage is attached fixedly, a reversible hydraulic motor for driving the endless belt reciprocably to cause the distributor carriage to distribute the strand to and fro between opposite ends of the reel upon which the strand is being wound, and a pair of hydraulic pumps operatively connected to the respective takeup reels for operating the hydraulic motor at any time at a speed proportional to the algebraic sum of the instantaneous rotational speeds of the takeup reels at that time.

6. Strand reeling apparatus which comprises a pair of takeup reels, separate drive means for rotating each of said takeup reels independently of the other, means for alternately transferring a strand being reeled from one of said takeup reels to the other, a distributor carriage slidably mounted for movement parallel to the longitudinal axes of said takeup reels, an endless belt to which the distributor carriage is attached fixedly, a reversible hydraulic motor for driving the endless belt reciprocably to cause the distributor carriage to distribute the strand to and fro between opposite ends of the reel upon which the strand is being wound, a pair of hydraulic pumps for supplying hydraulic fluid to operate the motor, said pumps being driven respectively by the separate drive means for the respective takeup reels at speeds directly proportional to the rotational speeds of said takeup reels, and means connecting the hydraulic pumps in parallel hydraulically whereby the hydraulic motor is operated at any time at a speed proportional to the algebraic sum of the instantaneous rotational speeds of the takeup reels at that time.
